COUPLING

Charles O. Merrill, Des Moines, Iowa

Application November 19, 1934, Serial No. 753,629

6 Claims. (Cl. 287—104)

The principal object of my invention is to provide a coupling that is capable of being easily and quickly placed in an assembled or disassembled condition.

5 A further object of this invention is to provide a coupling that is light in weight.

A still further object of my invention is to provide a coupler that is strong, economical in manufacture, and durable in use.

10 These and other objects will be apparent to those skilled in the art.

My invention consists in the construction, arrangement and combination of the various parts of the device, whereby the objects contemplated are attained as hereinafter more fully set forth, pointed out in my claims and illustrated in the accompanying drawing, in which:

Fig. 1 is a top plan view of my complete coupling in an assembled condition and ready for use.

Fig. 2 is a cross-sectional view of the barrel portion of my device, showing the construction of the manually operated safety lock.

Fig. 3 is a cross-sectional view of the barrel portion of the device, illustrating the construction and arrangement of the locking bar.

Fig. 4 is a top plan-sectional view of the coupler in an assembled condition and with the safety lock on.

30 Fig. 5 is a top plan-sectional view of my device with the elements in a position where they may be detached from each other and the coupler disassembled thereby.

Fig. 6 is a side-sectional view of the device assembled and with the safety lock on.

Fig. 7 is a cross-sectional view of my device, taken on line 7—7 of Fig. 1, and more fully illustrates its construction.

Much of our modern machinery and equipment requires the use of quick release coupling devices. The construction of my coupler is particularly adapted to the many uses of industry and although the drawing shows a coupler for connecting ropes, cables, chains, and the like, it will be obvious that the general construction also lends itself for use in connecting electrical lead lines, hose, etc.

Referring to the drawing, I have used the numeral 10 to designate the cylindrical barrel portion of my coupler. The numeral 11 designates the catch bar positioned near the inside center of the barrel 10, as shown in Fig. 4. This comparatively flat catch bar is rotatably mounted inside the barrel by two diametrically oppositely extending shafts 12 and 13, which are each ro-

tatably mounted in the case of the barrel 10. The numeral 14 designates a coil spring embracing the shaft 13, having one end engaging the catch bar 11 and its other end engaging the barrel 10. This spring 14 yieldingly holds the catch bar 11 to a position substantially that of the position of the bar shown in Fig. 3.

The numerals 15 and 16 designate the two engaging arms which are designed to be connected to the two elements to be secured together, respectively. In Fig. 1, I show the two elements to be detachably secured together, as chain links 17 and 18. The two engaging arms are duplicates and each arm has its free end that is designed to be inserted in the barrel rounded, as shown in Fig. 5. I have used the numeral 19 to designate a comparatively flat face on each of the engaging arms. These flat faces 19 extend longitudinally of the arms and are formed from the free end of each of the arms to a point near the attached end. When the two engaging arms are inserted into the two ends of the barrel portion these flat faces face each other and are designed to extend on either side of the catch bar. The numeral 20 designates a notch formed in each of the flat faces of each of the engaging arms. These notches are positioned near the free ends of the arms and as they face each other, are capable of being engaged by the two side edges of the catch bar, as shown in Fig. 4. Each of these notches 20 has its side wall closest to the free end of the arm extending at approximately a right angle to the longitudinal axis of the arm and its other side wall extending outwardly and rearwardly to the flat face 19 of the arm at an angle to the longitudinal axis of the arm, as shown in the drawing.

By this construction the coupling may be coupled together by merely inserting the arms 15 and 16 into the barrel to positions where the notches 20 are adjacent the catch bar 11. When in this condition the spring 14 will move the catch bar to an angle to the longitudinal axis of the barrel and into the notches 20. With the catch bar in this position it is obvious that the arms 15 and 16 cannot be withdrawn from the barrel as the two marginal edges of the catch bar are abutting the side wall of each of the notches that extend transversely of the longitudinal axis of the arms.

In order that the marginal side edges of the catch bar will conform with these transversely arranged side walls of the notches, the marginal side edges of the bar may be cut at an angle or tapered, as shown in the drawing. The rounded

forward free ends of the arms facilitate the introduction of the arms into the barrel and past the yielding catch bar.

To detach the coupling it is merely necessary to force one of the arms further into the barrel to a position where its notch is past the catch bar, as shown in Fig. 5. While one of the arms is in such a position the other arm may be withdrawn completely from the barrel. The reason for this is that the combined thickness of the arms and bar is substantially that of the inside diameter of the barrel and when one of the arms is forced inwardly the catch bar will ride out of the notch in that arm and onto the flat surface 19 of that arm, forcing the catch bar into a position longitudinally of the longitudinal axis of the barrel. With the catch bar in this position it will also be out of engagement with the notch of the other arm and this other arm may be slid therefore, out of the barrel without interference from the catch bar. From this it will be readily seen that my coupling can be either assembled or detached by merely grasping and moving the engaging arms 15 and 16.

Under certain conditions it may be desirable to definitely lock the coupling against detachment and therefore, in the drawing, I show an auxiliary safety lock or catch which I will now describe. The numeral 21 designates a longitudinal slot in the barrel 10, as shown in Fig. 6. The numeral 22 designates a spring band frictionally embracing the outside of the barrel. The numeral 23 designates a lug secured to the band 22 and loosely extending through the slot 21 into the barrel.

To prevent any releasing movement of the arms 15 and 16, the band is manually slid toward the center of the barrel where the lug 23 will contact and engage the catch bar, as shown in Fig. 4, and Fig. 6. With the lug engaging the catch bar, all the parts inside the barrel will be locked against movement. To release this auxiliary safety lock the band is slid away from the center line of the barrel and the lug out of engagement with the catch bar, at which time the arms 15 and 16 may be operated in the way herebefore described. Obviously, other means may be used to lock the arms and catch bar against movement at times.

Some changes may be made in the construction and arrangement of my improved coupling without departing from the real spirit and purpose of my invention, and it is my intention to cover by my claims any modified forms of structure or use of mechanical equivalents which may be reasonably included within their scope.

I claim:

1. In a device of the class described, a barrel member, a bar member rotatably mounted in said barrel member, a yielding means for holding said bar to one direction of its rotation, two arm members designed to extend into said barrel

member from opposite directions, and a notch in each of said arms capable of being engaged by said bar member.

2. In a coupling, a cylindrical member, a substantially flat bar member in said cylindrical member, a means for yieldingly holding said bar member at an angle to the longitudinal axis of said cylindrical member, detachable arms designed to extend into each end of said cylindrical member from opposite directions, and a depression in each of said arms capable of being engaged by said substantially flat bar member.

3. In a coupling, a cylindrical member, a substantially flat bar member in said cylindrical member, a means for yieldingly holding said bar member at an angle to the longitudinal axis of said cylindrical member, detachable arms designed to extend into each end of said cylindrical member from opposite directions, and a depression in each of said arms capable of being engaged by said substantially flat bar member at times; said two arms and bar having a combined thickness substantially equal to the inside diameter of said cylindrical member.

4. In a coupling, a cylindrical member, a substantially flat catch bar member inside said cylindrical member, a means for yieldingly holding said bar member at an angle to the longitudinal axis of said cylindrical member, two detachable arms designed to be inserted into each end of said cylindrical member respectively, a flat surface on each of said arms, and at notch formed in the flat surface of each of said arms capable of being engaged by the marginal side edges of said bar member at times.

5. In a coupling, a cylindrical member, a substantially flat bar member in said cylindrical member, a means for yieldingly holding said bar member at an angle to the longitudinal axis of said cylindrical member, detachable arms designed to extend into each end of said cylindrical member from opposite directions, a depression in each of said arms capable of being engaged by said substantially flat bar member at times; said two arms and bar having a combined thickness substantially equal to the inside diameter of said cylindrical member, and a means for locking said bar member against movement relative to said cylindrical member at times.

6. In a coupling, a hollow member, a catch bar member rotatably mounted in said hollow member, a spring for yieldingly holding said bar member transversely of said hollow member, a detachable arm designed to extend into each end of said hollow member, and a notch in each of said arms capable of being engaged by said bar member; said notch having one of its walls extending transversely of the length of said arm in which it is formed.

CHARLES O. MERRILL.
